UNITED STATES PATENT OFFICE

ELIOT ARMSTRONG, OF NIAGARA FALLS, NEW YORK, ASSIGNOR TO NIAGARA METAL STAMPING CORPORATION, OF NIAGARA FALLS, NEW YORK

CURTAIN OR OTHER ARTICLE SUPPORT OR BRACKET

Application filed July 15, 1925. Serial No. 43,758.

This invention relates to improvements in article supports or brackets, and particularly to devices of this character commonly known as curtain holders, which are used for the purpose of supporting the lower portions of window curtains and draperies in position at the sides of a window so as to prevent the curtains from dragging across the window sill, or against fly screens, thus becoming soiled when the window is open.

The objects of the present invention are to provide an improved curtain bracket or holder comprising an attaching member, and an arm adapted to be secured to the attaching member so as to extend horizontally therefrom in different angular relations, so that the brackets may be attached at opposite sides of a window or any adjacent vertical surface, regardless of whether said surface is parallel with or perpendicular to the window; also to provide a device of this character having quick detachable means whereby the arm may be readily secured to and removed from the attaching member; and also to provide a bracket having an arm provided with a portion at one end thereof for permitting said arm to be detachably secured to the attaching member of the bracket in a novel manner so as to extend horizontally therefrom in operative position, and with a part at the opposite end thereof for detachably securing the arm to the attaching member so that the arm will extend vertically downwards adjacent the supporting surface in an inoperative position and in which position the arm will be prevented from swinging about and rattling, said latter end part also constituting a curtain or article retaining portion at the outer end of the arm when said arm is in its operative position.

Other objects of the invention are to improve and simplify curtain supporting brackets or devices in the other respects hereafter specified and claimed.

In the accompanying drawings,

Fig. 1 is a horizontal section of a window sash and casing showing two curtain holding brackets, embodying this invention, ar-

ranged in operative position at opposite sides thereof.

Fig. 2 is a side elevation, on an enlarged scale, of my improved curtain holder.

Fig. 3 is a plan view showing the attaching member of the bracket and a portion of the arm thereof in one position in full lines, and in two alternative positions in broken lines.

Fig. 4 is a perspective view of the attaching member of the bracket, and one end of the bracket arm arranged thereon in its inoperative position.

Fig. 5 is a transverse section of the attaching member, and an end of the arm as it appears when being positioned in operative relation to said attaching member.

In the preferred embodiment of the invention shown in the drawings, the curtain holder or bracket includes an attaching member or plate 10 preferably formed of sheet metal and having a securing portion 11 provided with apertures 12 for the reception of screws or fastening devices 13 whereby said member may be rigidly attached to a vertical support or surface, and a retaining portion 14 extending substantially horizontally therefrom, and which is formed so as to detachably hold and retain a curtain engaging arm or member 15 in either an operative position, extending horizontally therefrom, or in an inoperative position depending in vertical relation thereto. The arm 15 is preferably formed from a length of round rod or wire, but can, if desired, be formed of other material.

The retaining portion 14 of the attaching member 10 is provided with means for permitting the arm 15 to be detachably connected thereto in the various positions stated, the means shown preferably comprising a plurality of holes or apertures 17, and the arm or rod 15 has the inner end thereof formed or constructed in a novel manner, whereby the same may cooperate with the apertures 17 to provide quick detachable means for securing the arm 15 in its operative position extending horizontally from the attaching member, the arm being maintained in such connection by its own weight. For this purpose, the aforementioned end of the

arm 15 is offset in two directions, as clearly shown in Figs. 2 and 5, so as to provide a hook having an upwardly extending short end 18, a substantially horizontally extending intermediate portion 19, and a short downwardly extending portion 20 connecting said portion 19 with the body portion of the arm, all of said portions 18, 19 and 20 preferably being disposed in a plane lengthwise 10 of said arm. Upon reference to the drawings, it will be noted that the apertures 17 in the attaching member 10 are disposed so that their centers, when connected by straight lines will form a square, one diagonal of 15 which extends parallel to the attaching portion 11, and the other diagonal of which extends perpendicular thereto. While the particular arrangement and disposition of the holes 17 shown provides the most compact arrangement, the holes 17 may be arranged or 20 disposed in other ways, as long as one or more pairs of holes are disposed in parallel relation to the supporting surface and one or more pairs of holes are disposed in perpendicular relation to said surface.

The distance between the axes of the portions 18 and 20 of offset end of the arm 15 is substantially equal to the distance between centers of diagonally opposite pairs of holes 30 17. Therefore, by passing the portion 18 of the arm into any one of the outer three holes 17, and moving the arm so as to bring the portion 20 thereof into this selected hole, as shown in Fig. 5, and then lowering the 35 outer end of the arm, the inner end 18 may be raised so as to enter the diagonally opposite hole 17 as shown in Figs. 1 and 3 and in dotted lines, Fig. 5, in which position the arm will be maintained by its own weight in horizontal position.

It will be readily seen, therefore, that by the construction described, including the arrangement of the holes 17, the arms may occupy either one of three positions with 45 reference to the attaching portion 10, as shown in Fig. 3, two of these positions being further illustrated in Fig. 1. The curtain bracket is, therefore, adapted for use in positions in which the vertical supporting surfaces for the brackets are disposed in different 50 angular relations.

The means provided in accordance with this invention for supporting the arm or rod 15 in an inoperative position on the attaching member 10 comprises a hook 22 formed on the outer end of the arm, and which includes an end or return portion 23 extending substantially parallel to the body portion of the arm towards the opposite end thereof. The 55 distance between axes of the portion 23 and the body portion of the arm is substantially equal to the distance between centers of adjacent holes 17 of the attaching member 10. If therefore the arm is tilted upwardly so as 60 to disconnect the end portion 18 from the

member 10, then by passing the portion 20 downwardly through that hole 17 in which it may be disposed, the body portion 15 may be continued downwardly through this hole until the outer hooked end is brought adjacent to the attaching member 10, whereupon the portion 23 may be passed into an adjacent hole 17, as shown in Fig. 4, thereby allowing the arm to depend vertically from the attaching member 10 adjacent the supporting 70 surface. Owing to the curvature of that portion of the hook member which lies between the end portion 23 and the body portion of the arm, said arm will be tightly held by friction in engagement with the sides of the holes 17 in which it is positioned. The arm is thus held substantially stationary, and is prevented from being moved by the wind or air currents, so that rattling of the arm against the supporting surface is prevented. 75

When the bracket or holder is in use the hooked outer end of the arm 15 acts to prevent the curtains from slipping off the arm. The bracket is also adapted to be used as a support for other articles, said hooked end being capable of maintaining the articles in position on the bracket. Obviously, if the distance between the outer end portion 23 and the body portion of the arm were equal to the distance between diagonally opposite holes 17 of the attaching member 10, this hooked end could be engaged in diagonally opposite holes 17 instead of adjacent holes, as shown. 90

While the attaching member 10 is shown as being formed of sheet metal, and the arm 15 is shown as being formed of a portion of round rod or wire, these members may be formed of other material, and the arm 15 and the holes 17 may be of other than circular shape if desired, without departing from the 100 spirit of this invention.

The curtain supporting bracket described is very simple, inexpensive to produce, calls for a minimum number of operations in its manufacture, being made of stock material such that detaching portion 10 requires only stamping to shape, and having the holes punched therein, while the rod 15 merely requires bending to shape. 110

The device is adapted to be used in a wide variety of situations, and in addition to its use as a curtain holder, may also be used as a supporting bracket for other articles, such as garments or the like, bird cages, and many other articles or objects. 115

I claim as my invention:—

1. In a bracket of the character described, the combination of an arm having an end thereof formed with a pair of spaced, offset portions, and an attaching member adapted to be secured to a support and including a horizontal plate having a plurality of spaced holes arranged in pairs in different angular relations to one another, whereby said end of the arm may be detachably connected to said 125 130

plate so as to extend in different directions therefrom, by threading the offset portions of said arm through the different pairs of apertures, the directions in which the arm extends 5 depending upon the particular pair of apertures with which the offset portions are engaged.

2. In a bracket of the character described, the combination of an arm having an end 10 thereof, formed with a pair of spaced, offset portions, and an attaching member adapted to be secured to a support, and having a plurality of spaced holes arranged in a group to form pairs of holes disposed respectively 15 in different diagonal relations to each other, said offset portions of said arm being adapted to loosely engage in different selected pairs of said holes, whereby said arm is adapted to be detachably connected to and extend from 20 said attaching member in different angular positions relatively thereto.

3. In a bracket of the character described, the combination of an attaching member adapted to be secured to a support and having 25 a flat, horizontal portion formed with a pair of apertures therein, a supporting arm having one end formed to be loosely and detachably connected in said apertures in said attaching member so that said arm may extend 30 horizontally therefrom in operative position, and said arm having its other end formed to engage in both of said apertures in a manner to permit said arm to be detachably connected to and depend from said attaching member 35 in an inoperative stationary position.

4. In a bracket of the character described, the combination of an attaching member adapted to be secured to a support and having a pair of apertures therein, a supporting 40 arm having one end bent to form offset portions adapted to be detachably engaged in said apertures in said attaching member to permit said arm to extend horizontally from said member in operative position, the other end 45 of said arm terminating in a U opening lengthwise of the arm and whose sides are detachably engageable in said apertures at one time, for supporting said supporting arm in an approximately vertical position.

5. In a bracket of the character described, the combination of an attaching member adapted to be secured to a support and having a flat, horizontal portion formed with pairs of apertures therein disposed in different angular relations to said support, and a supporting arm having one end formed with two offset portions adapted to extend into any selected pair of said apertures to permit said arm to project horizontally in operative 60 position at different angles relatively to said attaching member, said offset portions being detachably held in connection with said apertures by the weight of said arm.

6. A bracket device comprising a support- 65 ing member having an apertured plate-like

projection, and a rod terminating at one end in a laterally opening U-shape, with the distance between the arms of the U approximately equal to the distance between a pair of said apertures of said projection, whereby said rod may be detachably connected to said member by threading the arms of the U successively through said apertures, and resting the portion of the arm adjacent the U-shaped end upon the upper face of said projection, the opposite end of said rod being doubled back on itself to form another longitudinally opening U having its arms spaced apart a distance corresponding to the distance between the arms of the U at the said one end of the rod, whereby the rod also may be attached to said member so as to depend stationarily therefrom, by threading the U at said opposite end through said apertures successively.

7. A bracket device comprising a supporting member having an apertured plate-like projection, and a rod terminating at one end in a laterally opening U-shape, with the distance between the arms of the U approximately equal to the distance between a pair of said apertures of said projection, whereby said rod may be detachably connected to said member by threading the arms of the U successively through said apertures, and resting the portion of the arm adjacent the U-shaped end upon the upper face of said projection, the apertures in said member being arranged in pairs for interengagement by said rod, and said pairs being arranged in different relations to one another for supporting said rod in a plurality of different positions depending upon which pair of apertures said rod is engaged with.

8. A bracket device comprising an angular member of sheet metal with apertures in one of the arms thereof, and a rod of uniform size throughout its length bent angularly at one end to provide a laterally opening U-shaped terminal with the distance between the arms of the terminal approximately equal to the distance between a pair of apertures in said one arm of said member, whereby said rod may be detachably connected to said one arm of the member by threading the arms of the terminal successively through said pair of apertures and resting the portion of the rod adjacent said terminal upon the upper face of said apertured arm of the member.

9. A bracket device comprising an angular member of sheet metal with apertures in one of the arms thereof, and a rod of uniform size throughout its length bent angularly at both ends to provide U-shaped terminals, the terminals at one end having the opening of its U facing laterally and that at the other end having the opening of its U facing the said one end, the distance between the arms of each U being approximately equal to the distance between a pair of the apertures in one

arm of said member, whereby either end of said rod may be detachably connected to said member by threading the arms of the **U** at either end successively through said pair of apertures.

- 5 10. A bracket device comprising an angular member of sheet metal with apertures in one of the arms thereof, and a rod of uniform size throughout its length bent angularly at one end to provide a laterally opening **U**-shaped terminal with the distance between the arms of the terminal approximately equal to the distance between a pair of apertures in said one arm of said member, whereby said rod may be detachably connected to said one arm of the member by threading the arms of the terminal successively through said pair of apertures and resting the portion of the rod adjacent said terminal upon the upper face of said apertured arm of the member, the apertures in said member being arranged in pairs for interengagement by said rod, and said pairs being arranged in different relations to one another for supporting said rod in a plurality of different angular positions depending upon which pair of apertures said rod is engaged with.
